MANUFACTURE OF ALCOHOLS

Vladimir Ipatieff and Vasili Komarewsky, Chicago, Ill., assignors to Universal Oil Products Company, Chicago, Ill., a corporation of Delaware

No Drawing. Application September 1, 1933,
Serial No. 687,843

3 Claims. (Cl. 260—156)

This invention relates to the manufacture of alcohols from olefins, particularly olefins of a normally gaseous character such as are encountered in gases from hydrocarbon cracking operations.

In a more specific sense the invention has reference to a process for the manufacture of relatively low boiling alcohols using a particular class of acid catalytic reagents.

10 The gases from hydrocarbon cracking operations are characterized by a considerable content of olefins and these olefins constitute a primary source of reactive hydrocarbon materials, although this reactivity has been made use of commercially only to a limited extent. Ethylene has been used to manufacture ethyl alcohol by selective sulfonation and hydrolysis and similarly considerable quantities of isopropyl alcohol have been manufactured. In these processes the usual 15 method of operation is to pass the mixture of gaseous hydrocarbons through a stationary body of sulfuric acid of regulated strength (or countercurrent to descending streams of acid in treating towers) until a sludge containing acid esters is produced, after which alcohols are obtained 20 by distilling the sludge after dilution with water, or by distilling the sludge with steam.

In processes using sulfuric acid to produce alcohols from olefins difficulties are encountered 25 owing to the tendency of the sulfuric acid to oxidize and polymerize unsaturated hydrocarbons as well as to form the desired esters from which the alcohols are obtained by hydrolysis. Thus, in the case of various butylenes the formation 30 of polymers may exceed the formation of the desired acid esters and limit the yield of alcohol obtainable. By using the particular acid catalyst reagents and the method of operation comprised within the scope of the present invention 35 many of the undesirable side reactions are eliminated and the yield of alcohols is increased.

In one specific embodiment the invention comprises the treatment of olefinic gases or olefinic gas mixtures to obtain alcohols therefrom with 40 phosphoric acid containing metallic salts and/or oxides at pressures up to 10 atmospheres and temperatures up to 120° C.

According to the present process various metal compounds are used to promote the action of 45 phosphoric acid in producing alcohols from ole-

fins. Among the metals whose salts and oxides may be used may be mentioned zinc, manganese, molybdenum, iron, nickel, cobalt, etcetera. As a rule these metallic promoters are only used in quantities of 10% and less by weight of the acid 5 and frequently sufficient promoting action is obtained when using amounts of the order of 5%.

Various types of salts may be dissolved in or mixed with the acid catalyst, such as nitrates, chlorides, etcetera and, in the case of some 10 metals, good results are obtained when oxides are dissolved. Owing to the strongly acid character of phosphoric acid some of the salts added will be decomposed so that the weaker acid is displaced and the resultant fluid mixture contains 15 the phosphate of the metal in solution. However, the extent of this action will depend not only upon the relative strength of the acid radicals but upon the concentration of the phosphoric acid, the temperature of treatment, the amount 20 of metal compound added, etc. so that it is not intended to infer that in every case metal phosphates result.

It will be seen from the above brief enumeration of the various types of metal compounds 25 which may be used as promoters that a considerable number of alternatives of varying composition comprising phosphoric acid and metal compounds are possible. However, each catalyst mixture will exert its own specific action in any given case which will not be exactly equivalent 30 to the action of other catalyst mixtures of the same general character. When dealing with the varying types of olefins which occur in hydrocarbon gas mixtures, acid catalysts of specific composition may be chosen for producing optimum yields of alcohols. However, it is not always possible to predict the exact action of any given reagent but for a given type of cracked gas mixture produced in the normal operation of a 35 cracking plant it is practically always possible to select reagents from the present group which will produce satisfactory transformation of the olefins into good yields of alcohols.

It is preferable in most cases to employ the 40 ordinary commercial ortho-phosphoric acid (H_3PO_4) rather than any of the other acids of phosphorus although the invention is not limited to the use of the ortho acid. In general also the acid of approximately 90% concentration pro- 45

duces good results in practice although this concentration may also be varied as desired, both as a means of controlling the solubility of the added promoters and the rate and character of the hydrolysis which results in alcohol formation.

The following equations indicate the probable course of the main reactions leading to the production of alcohols by the present process:

15 The exact mechanism of the action of the different promoters is difficult to follow and, therefore, it is only possible to suggest what their action is. It may be that there is some intermediate formation of metal salt addition compounds from which the alcohols later result, or it may be that the action of the metal salt promoters is 20 more definitely catalytic and that such addition compounds if formed are very transient in character and not capable of separation and identification.

25 The details of process operation may be varied considerably and both batch and continuous types may be employed. In batch operation phosphoric acid and a small amount of a selected metal compound promoter may be added to a pressure vessel lined with some corrosion-resistant material and a pure olefin or an olefin-containing gas may be pumped into the bomb until a certain pressure is reached, after which the bomb is heated and the contents agitated either by rotating 30 the bomb or by mechanical stirring devices. The process is interrupted when the rate of absorption becomes too low as indicated by a stationary pressure and the liquid products comprising alcohols and some polymerized olefins are removed, after which the cycle is repeated using the same 35 catalyst mixture until its efficiency is lost due to the gradual accumulation of heavy polymers and high molecular weight acid esters. It is characteristic of the present invention that the deterioration of the catalyst is much slower than 40 that of other acid catalysts, particularly sulfuric acid, so that larger yields of alcohols are obtainable for a given amount of catalyst.

45 In continuous operations an acid catalyst mixture, water or steam and gaseous olefins may be 50 injected simultaneously in regulated proportions into tubular heaters through which the reacting components pass and from which they are discharged into a separator or a flash distilling unit. The acid catalyst is then withdrawn from 55 the bottom of the distilling chamber and returned to the entrance of the heating element for further use while the vaporous products of the reaction, both hydrocarbons and alcohols, 60 are passed through a fractionating column to obtain desired cuts containing different alcohols in case a mixture of olefins was used. The alcohols

in the distillate fractions may be purified and separated from hydrocarbon material by solution in water and a secondary distillation of the aqueous extract.

5 The following examples are characteristic of results obtainable by the use of the process and are introduced as illustrations but it is to be understood that many others are available.

Example 1

10 52 parts by weight of commercial 90% orthophosphoric acid and 5 parts by weight of black nickel oxide were added to a pressure vessel. 50 parts by weight of propylene were added under a pressure of 120 pounds per square inch after 15 which the temperature was raised to 120° C. and held there until constant pressure conditions obtained.

20 There was produced by this operation 25 parts by weight of liquid products comprising 60% isopropyl alcohol and 40% propylene polymers, principally dimers and trimers, which were of a character suitable for use as high anti-knock blending fluid in gasoline.

Example 2

25 50 parts by weight of 90% orthophosphoric acid and 5 parts by weight of commercial zinc chloride were added to a pressure treater. 50 parts by weight of propylene was added under a 30 pressure of 3 atmospheres and the temperature again raised to 120° C. and maintained at that point until constant conditions were observed.

35 In this case 22 parts by weight of liquid products were obtained, 62% of which consisted of isopropyl alcohol extractable by water and 38 parts of propylene polymers which as before were 40 utilizable as high anti-knock blending constituents for admixture with gasoline.

The foregoing specification and examples, while disclosing the character of the invention and giving selected results showing its practical value, are not to be considered as imposing undue limitation thereon.

We claim as our invention:

45 1. In the production of alcohol from olefin hydrocarbons, the step which comprises treating the olefin with a phosphoric acid solution to which nickel oxide has been added.

50 2. In the production of alcohol from olefin hydrocarbons, the step which comprises treating the olefin with a phosphoric acid solution to which has been added from about 5% to 10% by weight of a metal oxide.

55 3. In the production of alcohol from olefin hydrocarbons, the step which comprises treating the olefin with phosphoric acid in the presence of nickel oxide.

VLADIMIR IPATIEFF.
